UNITED STATES PATENT OFFICE.

THOMAS J. MURDOCK, OF FRANKLIN, MASSACHUSETTS, ASSIGNOR TO MURDOCK AND GEB COMPANY, OF FRANKLIN, MASSACHUSETTS.

BOBBIN-HOLDER.

SPECIFICATION forming part of Letters Patent No. 691,162, dated January 14, 1902.

Application filed June 27, 1901. Serial No. 66,199. (No model.)

To all whom it may concern:

Be it known that I, THOMAS J. MURDOCK, a citizen of the United States, residing at Franklin, in the county of Norfolk and State of Massachusetts, have invented a new and useful Improvement in Bobbin-Holders, of which the following is a specification.

This invention has reference to an improvement in bobbin-holders for spinning and twisting machines; and it consists in the peculiar and novel construction more fully set forth hereinafter.

Bobbin-holders in which the bobbin is held by means of spring-pressed clamping-arms have been heretofore provided with clamping-arms pivotally supported on a plate or member of the holder, the clamping-arms being usually separable members.

The object of this invention is to secure a more durable structure and reduce the cost of its manufacture. To this end I form the clamping-arms of one integral sheet of spring metal, inclose the same in a sheet-metal and non-resilient cup, and secure to a sleeve which is in turn secured to the spindle.

Figure 1 is a side view of a spindle provided with a bobbin secured by my improved bobbin-holder. Fig. 2 is a transverse sectional view of the bobbin, showing the bobbin-holder. Fig. 3 is a vertical sectional view of the bobbin and bobbin-holder. Fig. 4 is a plan view of the dished spring-plate, against which the base of the bobbin bears. Fig. 5 is a top view of the clamping-arms, showing them formed of one integral sheet. Fig. 6 is a plan view of the cup forming the base of the bobbin-holder.

Similar marks of reference indicate corresponding parts in all the figures.

In the drawings, A indicates the spindle; B, the bobbin; b, the head of the bobbin, and b' the groove in the periphery of the bobbin-head. The bobbin-holder consists of the cup C, the clamping-plate D, the spring-plate E, and the sleeve F. The cup C is stamped up of rigid sheet metal and has the central hole c, the inclined annular bottom c', and the cylindrical rim c². The clamping-plate D, formed of a sheet of spring sheet metal, is cut in suitable dies to form the central ring d, the spring-necks d', and the clamping-arms d² d³. The whole is now placed onto a former

and the clamping-arms are bent and set to the form shown in Fig. 3, having the inwardly-inclined concavo-convex lower portion d³ and the outwardly-inclined concavo-convex upper portion d⁴. When the clamping-arms are bent over a former, they are preferably rolled on the outer surface to shape them and to set the metal and insure a reliable spring action. The clamping-plate E is stamped up of spring sheet metal and has the central hole e and the bearings e' e' projecting from the peripheral edge. The plate is dished, so as to give incline to the annular surface. The sleeve F consists of a short tubular body having one end enlarged to form an annular shoulder.

In assembling the parts the cup C is placed on the sleeve and on top of it the clamping-plate D, upon which is placed the spring-plate E, so that the clamping-plate D is interposed between the parts C and E upon the sleeve F. The end of the sleeve F is now upset in a die, and the parts C, D, and E are firmly secured to the sleeve F between the annular shoulder and the annular head formed by the upsetting of the end of the sleeve. The sleeve F is now driven onto the spindle or otherwise secured to the same. When in use, the base of the bobbin readily enters between the outward-inclined surfaces d⁴ of the clamping-arms d². Force being applied to the bobbin, the clamping-arms yield outwardly until they bear against the rim c² of the cup C, when, if the bobbin-head does not pass by the contracted portion of the clamping-arms, extra force is required to insert the bobbin-head. The base of the bobbin-head bears when properly inserted on the spring-plate E. The groove b' in the peripheral surface of the bobbin-head facilitates the holding of the head by the contracted part of the clamping-arms at the intersection of the inclined portions d³ and d⁴, partly entering the groove.

When the plate D with the clamping-arms is formed of sheet metal of sufficient thickness and the clamping-arms are bent and set so as to insure the required resiliency, the holder will firmly retain the bobbin. In the preferred form shown in the drawings the plate D and the clamping-arms are of thinner metal, and the resiliency is augmented by the use of the ring G, formed of spirally-wound wire, inclosing the clamping-arms. In this

preferred form the bottom c' of the cup C materially aids the clamping-arms d^2 d^2 to resist the force exerted to insert the bobbin.

Having thus described my invention, I 5 claim as new and desire to secure by Letters Patent—

1. The combination of a spindle, a bobbin-holder comprising an annular member provided with a set of outwardly-projecting 10 spring-necks each having a clamping-arm adapted to grip the head of the bobbin, and an annular spring-plate secured within said bobbin-clamping member for supporting the bobbin and pressing the same upwardly 15 against the spring action of said clamping members, substantially as described.

2. The combination of a spindle, a bobbin-holder comprising an annular member provided with a set of outwardly-projecting 20 spring-necks each having a clamping-arm adapted to grip the head of the bobbin, and an annular cup-shaped body having a convexed bottom secured beneath said bobbin-clamping member, the under side of said 25 clamping member resting upon the high part of said convexed bottom, substantially as described.

3. The combination of a sleeve adapted to be fixed upon a spindle, an annular member 30 secured to said sleeve and provided with a set of radial spring-necks each having a comparatively rigid clamping-arm adapted to grip the bobbin, an annular cup-shaped body se-

cured beneath said clamping member and the sides of the said cup-shaped body serving as 35 a stop for limiting the outward movement of said clamping-arms when inserting the bobbin, and a concavo-convex spring-plate secured to said sleeve above and within the said clamping member for receiving the base of 40 the bobbin and supporting the same, substantially as described.

4. The combination of a sleeve F adapted to be fixed upon a spindle, the annular member D secured to said sleeve and provided 45 with a set of radial spring-necks each having a comparatively rigid clamping-arm adapted to grip the bobbin, the annular cup-shaped body C secured beneath said clamping member, the sides of said cup-shaped body serving as a 50 stop for limiting the outward movement of said clamping-arms when inserting the bobbin, a concavo-convex plate E secured to said sleeve above and within said clamping member and supporting the same, and the auxiliary spring-ring G to assist the clamping-arms in gripping the bobbin, substantially as described.

In testimony whereof I have signed my name to this specification in the presence of 60 two subscribing witnesses.

THOMAS J. MURDOCK.
